UNITED STATES PATENT OFFICE.

EDWARD BERLES, OF CHICAGO, ILLINOIS, ASSIGNOR TO JOHN C. MONINGER COMPANY, OF CHICAGO, ILLINOIS, A CORPORATION OF ILLINOIS.

GEARING.

1,223,754.

Specification of Letters Patent. Patented Apr. 24, 1917.

Application filed July 21, 1916. Serial No. 110,538.

To all whom it may concern:

Be it known that I, EDWARD BERLES, a citizen of the United States, residing at Chicago, in the county of Cook and State 5 of Illinois, have invented certain new and useful Improvements in Gearing, of which the following is a specification.

My invention relates to improvements in gearing and more particularly to a mechanism for opening or closing a green-house window.

One of the objects of the invention is to provide a simple and inexpensive rack and pinion with a connection for holding the rack, at all times, in engagement with the pinion.

Another object of the invention is to provide such a device in which the connecting member for holding the rack in contact with 20 the pinion, engages the rack side of the pinion member and does not encircle the pinion and shaft as has sometimes been the practice heretofore.

Other objects are to provide a rugged, 25 sturdy, inexpensive apparatus, easily assembled and applied, and not liable to become clogged or get out of order.

Still further objects will become apparent to those skilled in the art from a consideration of the following description and drawings wherein:—

Figure 1 is a transverse vertical section through a green-house roof showing my improved apparatus mounted for raising and 35 lowering opposite window sashes.

Fig. 2 is an enlarged side elevation of the apparatus.

Fig. 3 is a sectional view on the line 3—3 of Fig. 2, and

40 Fig. 4 is a fragmentary sectional view on the line 4—4 of Fig. 2.

It is customary in green-houses and similar places, where a plurality of windows are to be controlled, to place a shaft in close 45 proximity to the windows and connect the windows with the shaft in such a way as to cause opening or closing thereof on rotation of the shaft. Suitable gearing of one sort or another connects the shaft with a 50 hand wheel or crank near the floor.

In the drawings I have illustrated the roof structure of a green-house at 10, with windows 11 and 12, on opposite sides. A tubular shaft 13 extends along the roof of 55 the house in close proximity to the lower

end of the window 11 and a similar shaft 14 extends adjacent the lower end of the window 12. Sprockets 15 and chains 16 are provided for manipulation of the shafts from the floor level.

Opposite each window is provided an annulus or collar 17 secured on the shaft by means of set screw 18. Gear teeth 19 are formed on one side of the annulus for engagement with the rack 20, the outer end 65 of which is pivotally connected with the window sash, as at 21. To hold the rack in engagement with the teeth of the pinion I provide a guide member comprising two side plates 22, 23, each having a pair of 70 outwardly extending legs 24 which project beyond the rear face of the rack and are joined by the bolts 25, on which are journaled rollers 26 for engagement with the rear face of the rack. The outer central 75 portion of the two members 22, 23 project across the back of the rack, as at 28, and are secured together by means of the bolt 29.

A pair of grooves 30, 31 are undercut in the axially opposite faces of the annulus 80 17 and serve as guide-ways into which project the arcuate fingers 32, 33 formed respectively on the inner ends of the guide members 22, 23. These arcuate fingers engage the grooves at the rack side of the 85 annulus and insure positive connection between the teeth of the rack and pinion at all times, at the same time permitting relative movement of the rack with its guide about the axis of the shaft.

Whereas I have illustrated and described a single embodiment of my invention, it is obvious that various changes may be made in the structure thereof without departing from the spirit and scope of the 95 following claims.

Having described my invention, what I claim is:—

1. The combination with a rotatable shaft of an annulus member thereon having a set-screw receiving hub and at one end a pinion, both ends of said member having undercut grooves forming with the shaft a pair of oppositely opening annular channels with concentric inner and outer walls, 100 a rack for engagement with the pinion, a rack guide comprising a carriage straddling the rack and having an abutment for the back of the rack to hold it in engagement with the pinion, and fingers projecting from 105

the carriage into each of the aforesaid channels at the side of the shaft adjacent the rack.

2. The combination with a rotatable shaft 5 of a pinion thereon, means for securing the pinion to the shaft, both ends of said pinion having undercut grooves forming with the shaft a pair of oppositely opening annular channels with concentric inner and outer walls, a rack for engagement with the pinion, a carriage straddling the rack and providing an abutment for the outer face thereof to hold the same in engagement with the pinion, and arcuate fingers projecting from each side of the carriage for engagement with the aforesaid channels at the side of the shaft adjacent the rack.

3. The combination with a rotatable shaft

of a pinion thereon, means for securing the pinion to the shaft, each end of said pinion 20 having oppositely opening annular channels, a rack for engagement with the pinion, a carriage straddling the rack and providing an abutment for the outer face thereof to hold the rack in engagement with the 25 pinion, and fingers projecting from each side of the carriage for engagement with the aforesaid channels at the side of the shaft adjacent the rack.

In testimony whereof I hereunto set my 30 hand in the presence of two subscribing witnesses.

EDWARD BERLES.

In the presence of—

RUDOLPH KUROWSKI,
CHESTER P. GRIOR.
